MUFFLER

Quintin G. Noblitt and Edmund Ludlow, Columbus, Ind., assignors to Noblitt-Sparks Industries, Inc., Columbus, Ind., a corporation of Indiana

Application September 2, 1941, Serial No. 409,239

2 Claims. (Cl. 181—54)

Our invention relates to silencers, and particularly to silencers for use in silencing the exhaust of internal-combustion engines. It is our object to produce silencers which can be simply and economically manufactured, which will possess an effective silencing action, and which will produce a relatively low back pressure.

In practicing our invention, we subject the gases to the action of side silencing chambers, both tuned and untuned. In addition, we divide the gases into two or more components, cause the components to flow over paths of different lengths, and then recombine them to silence sounds of more or less definite wave lengths as the result of interference effects. Desirably, the gases are subjected to the action of the untuned side silencing chambers before being divided.

The accompanying drawing illustrates our invention, Fig. 1 being a longitudinal section through a silencer and Fig. 2 a transverse section on the line 2—2 of Fig. 1.

The muffler illustrated in the drawing comprises a cylindrical shell 10 which, as indicated in Fig. 2, is conveniently of a general elliptical shape in cross-section, but which may have any convenient cross-sectional form. The front and rear ends of the shell 10 are closed respectively by heads 11 and 12. Spaced longitudinally from these heads and from each other are two transverse partitions 13 and 14 through which there extend three tubes 15, 16, and 17. The front end of one of these tubes, here shown as the tube 15, is connected to an inlet nipple 18 which extends through the front head 11 and is adapted at its front end for connection to the exhaust pipe of an internal combustion engine. Another of the tubes, shown as the tube 16, communicates at its rear end with an exhaust nipple 19 which projects rearwardly through the head 12 and is adapted at its rear end for connection to a suitable tail pipe.

Between the front head 11 and the partition 13 we mount a transverse partition 21 which co-operates with the head 11 to define a silencing chamber 22 and with a partition 13 to define a transverse passage 23 interconnecting the front ends of the tubes 16 and 17. A similar partition 24 near the rear end of the casing 10 co-operates with the head 12 to define a second silencing chamber 25 and with the partition 14 to define a transverse passage 26 interconnecting the rear ends of the tubes 15 and 17.

Extending through the partition 21 is a tube 30 providing a restricted neck through which

the silencing chamber 22 communicates with the passage 23. A similar tube 31 extending through the partition 24 provides communication between the silencing chamber 25 and the passage 26. As is well known each of the chambers 22 and 25, with its associated neck 30 or 31, serves to absorb sounds of more or less definite frequency depending upon the volume of the chamber and upon the cross-sectional area and length of the neck.

As will be clear from Fig. 1, the tube 15 is provided with a multiplicity of perforations extending throughout its length, such perforations desirably being in the form of narrow, circumferentially extending slots 33. The space between the partitions 13 and 14 is preferably divided into a plurality of silencing chambers 34, 35, 36, and 37 by transversely extending partitions 38.

As so far described, the muffler of this application is the same as that set forth in our co-pending application, Serial No. 409,238, of even filing date herewith. The muffler of this application, however, differs from that of the other in that the conduit formed by the aligned tube 16 and discharge nipple 19 is not provided with an opening permitting the direct admission of gases from the transverse passage 26. Instead, the tube 16 and discharge nipple 19 have a reasonably tight telescoping fit which prevents any gases from entering from the transverse passage 26. An additional difference between the muffler of this application and the muffler of our other application just mentioned lies in the fact that for a limited portion of its length 35 the tube 16, and desirably also the tube 17, is provided with a multiplicity of perforations 33 similar to those in the tube 15. As shown, both the tube 16 and the tube 17 are provided with such perforations; and in the case of each 40 tube the perforations are confined to that portion of the tube lying within the rearmost side silencing chamber 37.

In the operation of the muffler above described, the exhaust gases enter the front end of the tube 15 through the nipple 18. As they pass through the tube 15, some of the gases in high-pressure zones pass outwardly through the openings 33 into the side chambers 34, 35, 36, and 37 and return to the tube when low-pressure zones pass therethrough. Thus, the chambers 34, 35, 36, and 37 act as untuned, or as relatively broadly tuned, side silencing chambers tending to suppress sounds over a fairly wide range of frequencies.

Some of the gases escaping from the tube 15

through the openings 33 into the silencing chamber 37 will flow transversely of the muffler and enter the tube 16 through the openings 33 therein. To a certain extent, the same sort of transverse gas-flow can exist through the chamber 37 from the tube 17 to the tube 18. However, the larger portion of the gases entering the tube 15 will flow therethrough and enter the transverse passage 23 from which they will escape through the tube 17, transverse passage 23, and tube 18 to the exhaust nipple 19. Because of the difference between the lengths of the paths followed by the gases entering the tube 16 from the compartment 37 and the gases which flow through the tube 17 and transverse passage 23, interference effects will occur when the gases are recombined in the tube 16; and, as is well known, such interference effects will tend to silence sounds of more or less definite frequency.

As pointed out in more detail in our co-pending application above referred to, the arrangement of slots 33 and chambers 24 to 37 is adapted to suppress relatively high sound frequencies over a fairly broad band, the silencing chambers 22 and 25 are respectively adapted to suppress more or less definite and relatively low frequencies, while the interference phenomena occurring within the tube 16 are adapted to suppress a more or less definite frequency lying within an intermediate range. As in the device of such co-pending application the possibility of gas-flow through the chamber 37 from the tube 15 directly into the tube 16 permits a portion of the gases, after having been subjected to the silencing action of the chambers 24, 25, and 35 and the slots 33 associated with them, to enter the rear portion of the tube 16 without passing through the tube 17 and front portion of the tube 16 and without being subjected to the action of the silencing chambers 22 and 25. Similarly, the slots in the rear portion of the tube 17 permit a second portion of the gases, after having been subjected to the silencing actions of the slots in the tube 15 and of the chamber 25, to enter the tube 16 without passing through the front portions of the tubes 16 and 17 and without being subjected to the action of the silencing chamber 22.

The division of the gases into portions which follow paths of different lengths before being recombined and discharged from the silencer not only causes the interference phenomena which are effective to suppress sounds of intermediate frequency but also reduces back pressure, as more fully explained in our co-pending application, Serial No. 409,238. In the silencer of this application, however, there are a plurality of paths of different lengths over which the gases may flow; and, as a result, the interference phenomena created when the gases recombine tend to suppress sounds of a number of frequencies rather than

sounds of a more or less definite single frequency, as in the silencer of our other application.

We claim as our invention:

1. In a silencer, an elongated casing having front and rear ends, a pair of main transverse partitions disposed in said casing and spaced from the ends of the casing and from each other, three tubes extending longitudinally of the casing between said main partitions, a conduit for conveying gases to the front end of the first of said tubes, means providing a rear transverse passage interconnecting the rear end of said first tube and the rear end of the second of said tubes, means providing a front transverse passage interconnecting the front ends of the second and third tubes, a tuned silencing chamber communicating with one of said transverse passages, and a supplementary transverse partition subdividing the space between said main partitions and within the casing, said first tube on both sides of said supplementary partition and said third tube only in rear of said supplementary partition being provided with a multiplicity of longitudinally distributed openings providing restricted communication between the interior of the respective tubes and the space surrounding them.

2. In a silencer, an elongated casing having front and rear ends, a pair of main transverse partitions disposed in said casing and spaced from the ends of the casing and from each other, three tubes extending longitudinally of the casing between said main partitions, a conduit for conveying gases to the front end of the first of said tubes, means providing a rear transverse passage interconnecting the rear end of said first tube and the rear end of the second of said tubes; means providing a front transverse passage interconnecting the front ends of the second and third tubes, a tuned silencing chamber communicating with one of said transverse passages, and a supplementary transverse partition subdividing the space between said main partitions and within the casing, said first tube on both sides of said supplementary partition being provided with a multiplicity of longitudinally distributed openings providing restricted communication between the interior of such tube and the space surrounding it, and said third tube being provided in rear of said partition with an opening providing restricted communication with the space surrounding it whereby a portion of the gases admitted to said first tube can flow transversely of the casing from said first tube to said third tube through the space in rear of said supplementary partition, said second and third tubes in advance of said partition having imperforate walls.

EDMUND LUDLOW.
